UNITED STATES PATENT OFFICE.

ARCHIBALD McCALLUM, OF HALIFAX, ENGLAND, ASSIGNOR TO THE
BIGELOW CARPET COMPANY, OF CLINTON, MASSACHUSETTS.

DESIGN FOR A CARPET.

SPECIFICATION forming part of Design No. 12,358, dated July 12, 1881.

Application filed May 21, 1881. Term of patent 3½ years.

To all whom it may concern:

Be it known that I, ARCHIBALD McCALLUM, of Halifax, England, have invented a new and original Design for Carpets, of which the following is a specification.

5 This invention relates to a new and original design for carpets and similar fabrics; and it consists in the novel grouping and configuration of figures hereinafter more fully described.
10 The accompanying drawing illustrates a face view of a carpet having my new design.
The group A is composed of a figure, B, somewhat resembling a pine-apple, growing upon a vine, from which vine also projects the
15 leaf-like figure a, with smaller leaf-like figures projecting therefrom. From the same vine projects the figure C, composed of a leaf dividing into three parts, with buds b and d growing from the end of one division. The figures
20 e and f somewhat resemble oak-leaves and grow on the same vine, as does also the figure g, resembling a half-open bud, and the figure G, resembling a flower with its petals turned very far backward. The leaf-like figure E
25 grows farther along this vine-stem, from which also projects the open flower-like figure D. From the end of the vine projects the figure H, resembling a cluster of grapes protruding from surrounding leaves. From this figure H
30 projects on one side the figure h—a branch bearing fruit resembling oranges. On the other side projects the figure i—a branch bearing leaves and buds.

The above-described figures form the group or vine A, and the repetition of this group A 35 at regular intervals over the background forms the design.

The background is composed of the group I, consisting of a series of bars with crosses at each end, set at right angles to each other and 40 forming a regular pattern; also, of the group K, consisting of a series of squares, each containing a figure like a Maltese cross in its center and four small squares at the four corners. A portion of the background is plain. 45

I claim—

1. The design for the background of carpets, consisting of the group, I, of crossed bars, substantially as shown. 50
2. The design for the background of carpets, consisting of the group, K, of Maltese crosses and squares, substantially as shown.
3. The design for carpets, consisting of the group A, containing figures B a C b d e f g D E G H h i, substantially as shown. 55
4. The design for carpets, consisting of the group A, containing figures B a C b d e f g D E G H h i, the background I, and background K, substantially as shown.

ARCHIBALD McCALLUM.
